(57) **CLAIM**

The ornamental design for a key shaped clip design for permitting key rings to be attached thereto, as shown and described.

DESCRIPTION

FIG. 1 is a front side elevational view of the key shaped clip design for permitting key rings and the like to be attached thereto.

FIG. 2 is a left side elevational view of the key shaped clip design for permitting key rings and the like to be attached thereto of FIG. 1 with the right side elevational view being the same view which shows the curved end portion with a protrusion in the inside surface thereof to provide a better grip on a key ring or the like.

FIG. 3 is a rear side elevational view of the key shaped clip design for permitting key rings and the like to be attached thereto of FIG. 1.

FIG. 4 is a top view of the key shaped clip design for permitting key rings and the like to be attached thereto of FIG. 1; and,

FIG. 5 is a bottom view of the key shaped clip design for permitting key rings and the like to be attached thereto of FIG. 1.
